AGGLOMERATING DEVICE

Frank Derfler, East St. Louis, Ill., assignor to
 Aluminum Company of America, Pittsburgh,
 Pa., a corporation of Pennsylvania

Application February 3, 1944, Serial No. 520,969

4 Claims. (Cl. 259—3)

1

This invention relates to devices by which powdered materials may be formed and compacted into shapes which are usually, but not necessarily, ball-like or roughly spherical in form.

Processes of handling powdered material, usually together with a binder, in such manner that the particles of the material are pebbled or agglomerated into various shapes are well known. The present invention has, among its objects, the provision of devices for practicing such processes which eliminate extensive handling of the materials being processed; which form and compact the materials continuously while returning undersized or incomplete shapes for further processing; which are compact, inexpensive and contain a minimum of moving parts; which, being continuously operable, may be utilized to avoid batch or lot processing; which operate without constant attention of the operator, and in which the forming and compacting of the powdered material may be continuously performed when means are provided for delivering the material to the operation at a predetermined rate of flow.

The invention may be best described and explained with reference to the embodiment thereof shown in the accompanying drawing in which like numerals designate like parts.

In the drawing:

Fig. 1 is an elevational view in cross section of a device embodying this invention.

Fig. 2 is a further cross sectional view at right angles to the view of Fig. 1, taken at the point indicated by the line 2—2 in Fig. 1.

As shown in the drawing, the devices comprise a structure formed of two elongate concentric chambers 10 and 11 separated by a common wall and having delivery means for transferring material from the processing chamber 10 to the sorting chamber 11 (said means being here shown as vanes 12 and openings 26) and means such as the perforate wall of chamber 11 for returning to the tumbling operation under-sized or incomplete shapes as well as material which has failed to compact and form into shape during its first passage through the tumbling chamber, provided also are means such as helixes 22, 24 for insuring positive directional movement of the material.

The materials may be brought to the devices in any suitable way, but where the mechanism is to be used for processing a predetermined flow of powdered material, an automatic delivery device, such as the screw device indicated at 13, for feeding the said flow to the chamber 11 is desirable auxiliary equipment. Also desirable in many cases is a means for feeding binder to the tum-

2

bling chamber where binder must be used in order to secure the agglomeration of the powder into shape. In some cases the binder, particularly if it be a solid, may be fed with the material. In other cases it may be separately fed, either in whole or in part, through some device, such as pipe 14, if the binder is liquid, or a gravity feed or screw feed may replace pipe 14 if the binder is a solid.

More specifically the apparatus shown in the drawing consists of a rotatable cylinder 10 forming a tumbling chamber and mounted on trunnions 15. The cylinder is rotated by drive shaft 16, movement to said shaft being imparted from a motor indicated at 18 through sprocket 17 and chain 18. All of these parts are mounted on the frame 20. A retaining ring 21 is fixed to the outer end of the cylinder or chamber 10 and the width of this ring controls the depth of the material which will be held in the rotating chamber during processing. This ring may be permanently fixed to the chamber, but since it controls the depth and, consequently, the weight of material processed, which is in turn a factor in the degree of compaction or hardness of the finished shape, it is desirable to provide detachable rings so that the ring size may be changed to positively control variations in depth of material being processed, which might result from uneven operation of the delivery device 13. A helix 22, or similar means, is fixed on the inner surface of the chamber 10 to insure positive movement of the material being processed towards the rear of the chamber during operation.

The inner or sorting chamber 11 is preferably supported from the rear, and end, wall 23 of the chamber 10 so that both chambers rotate at the same speed. It will be apparent, however, that chamber 11 may be separately rotated, if desirable or if operating circumstances should so require, in which case this chamber may be separately suspended in the outer chamber on a suitable shaft and separately rotated. The open end of chamber 11 registers with the open end of chamber 10 and a helix 24, or similar device, provided on the inner surface of chamber 11 positively feeds any material in the chamber to said open end where such of the shapes as are of finished size fall into a hopper or gravity transfer device, such as indicated at 25. At least one opening or port 26 is provided at the rear end of chamber 11 and vanes 12 attached to end wall 23 are so positioned relative to said openings that as chamber 10 rotates they pick up material fed to the rear of the chamber and positively guide the fall of said material through the openings. An

inclined surface 28 is so positioned in chamber 11 and relative to openings 26 as to immediately guide material falling through said openings away from the area of the openings so that said material does not register with said openings and return to chamber 10 during rotation of the device. Plates 12' attached to said surface 28 and extending to the wall of chamber 11 serve as continuations of the vanes 12 and prevent material dropping into the chamber 11 from sliding around the surface 28 and through a lower opening 26. All, or a portion, of the wall of chamber 11 is perforated with openings 29 of predetermined size, through which the formed and compacted shapes which are of proper size will not pass but through which unformed material and incomplete and under-sized shapes will again return to the chamber 10 for further processing. It is, however, desirable to provide a perforate chamber wall only, as shown, at the outer end of chamber 11 and to so construct the perforate portion of the chamber 11 wall that it may be easily detached from the remainder of the chamber and replaced with another wall portion having perforations 29 of greater or less size. In this way the device may be made flexible to deliver any predetermined size of formed and compacted shapes as a final product.

In the preferred form of the invention herein illustrated an open end hopper 27 surrounds the perforate portion of the inner chamber 11 and receives material therefrom which thereafter falls from the hopper into the outer chamber. The principal function of hopper 27, which is attached to chamber 11, is to provide a chamber in which partially agglomerated particles, or other unfinished material, may be further treated with binder before returned to the chamber 10 for further processing. When this hopper 27 is used, the binder delivery means, here represented by the pipe 14, may feed directly into the hopper as shown, or two binder feeders may be provided, one to feed binder to the material in the hopper and one to feed binder to the material in the chamber 10. The hopper 27 also serves as a shield to prevent unagglomerated material in chamber 10 from falling into chamber 11 through perforations 29.

While the above description is of a preferred embodiment of the invention, it will be apparent therefrom that the devices described broadly comprise an inner chamber, an outer chamber, a passageway for the transfer of materials from the outer to the inner chamber, means for returning under-sized shapes to the outer chamber for further processing and means for establishing and maintaining a progressive flow of material from its point of entry into the outer chamber through that chamber into the inner chamber and through the inner chamber to the points where unfinished material is returned to the outer chamber for further processing and finished shapes of predetermined size are delivered. Thus the invention admits of several modifications, some more useful than others, depending upon the agglomerating problem at hand. For instance, the shielding means described for preventing back flow of materials through openings 29 may be disposed with or other obvious means provided. The inner chamber may be rotated for best results, but if desired, it may be stationary, in which case movable means, such as rakes, may be substituted for the helix 24 to insure positive movement of the material over the openings 29 and to the

delivery end of the chamber. Likewise, if the materials are free flowing, means, such as helix 24, may be replaced by sloping the walls of the chamber to maintain gravity flow to the open end thereof. Again where the exigencies of the operation are such that delivery of the under-sized shapes directly to the outer chamber through openings provided between the delivery means and the exit, or open end, of the inner chamber is undesirable, the length of the inner chamber may be extended out of and beyond the outer chamber and the openings, such as 29, so arranged in the extended portions as to deliver the under-sized to a device by which the under-sized are indirectly returned to the outer chamber. These and similar modifications of the principles and mode of operation of the invention will be readily understood by those skilled in the art.

The simplicity and efficiency of the operation of the preferred devices of this invention is immediately apparent. Powdered material which is to be formed and compacted into shape is placed in the outer chamber 10 at the front, or open end, portion thereof. Motor 19 is started causing rotation of the device. At the start a binder is mixed with the powder in chamber 10 in some suitable way, as above indicated, and rotation of the binder and powdered material in the chamber causes, as is known, the powdered material to agglomerate or ball up into compact masses or shapes. As rotation proceeds, the material under process is gradually displaced toward the rear of the chamber by helix 22. At the rear of the chamber the material, which is constantly being lifted by the rotation of the device, falls over vanes 12 through the openings or passageway 26 into chamber 11, where helix 24 guides the material toward the front, or open end, of chamber 11 over the perforate portion of the walls of said chamber. Material not formed and compacted into shapes of the desired size falls through the perforations in the chamber wall into hopper 27, if said hopper is provided, or directly into chamber 10, if hopper 27 is not used. In the hopper 27 the partially agglomerated and unagglomerated material is again treated with binder through pipe 14 and eventually, due to the rotation of the device and the inclined surface of the hopper, the material again falls into chamber 10, where it becomes mixed with the material under process and is recycled. The formed shapes which are of proper size and which come into chamber 11 through openings 26 move over the perforate portions of the wall of that chamber and fall from the chamber's open end into the disposal device 25.

Because of compactness and lack of moving parts, the devices of this invention are particularly adapted to commercial operations where a large bulk of material is handled. The device may be operated on material that is intermittently fed to the outer chamber in batches, but considerable advantage is derived if the powdered material and the binder, if necessary, are furnished to chamber 10 at a predetermined rate of flow. It will be noted that once the proper materials are furnished to the tumbling chamber 10 and the rotation of the device is initiated, only a finished product is delivered, while the under-sized is continuously recycled until it has achieved proper size. Therefore, once the flow of material into the apparatus is established at a rate equal to the flow of finished material from chamber 11 into disposal device 25, the operator

has no further duties except to receive the finished article.

At the start of such an operation as above described, it is often necessary or desirable to furnish partially agglomerated or "seed" shapes to the mass of powdered material in order to initiate the forming and compacting operation. Usually it has been customary to obtain this seed by crushing finished shapes to proper size and feeding the crushed material to the operation with the powdered material. The present device, however, may eliminate partially or completely the necessity for this separate seeding operation (except at the very beginning of the process), because the partially agglomerated or shaped particles which fall through the perforate portion of the sorting chamber automatically return to the processing or tumbling chamber and furnish the desired seed. However, in some instances it may be desirable to add seed at intervals.

While the means and mode of operation which characterize this invention have been described with the relation to a specific embodiment thereof, it will be apparent to those skilled in the art that other embodiments may be constructed without departure from the mode of operation and basic arrangement of parts herein described.

I claim:

1. A device for forming and compacting powdered materials into shapes of predetermined size, said device including a rotatable structure containing outer and inner elongate concentric chambers separated by a common wall and connected adjacent one end with a passageway through which materials contained in the outer chamber may be passed to the inner chamber during rotation, means for rotating said structure, openings disposed in said common wall at points removed from said passageway, said openings being dimensioned to prevent passage therethrough of shapes of said predetermined size, a chamber intermediate said outer and inner chambers into which materials passing through said openings fall said chamber having an opening at one end thereof whereby materials contained therein will, during rotation, be passed to said outer chamber, means for applying a binder to materials in said last mentioned chamber, means for progressively moving material in the outer chamber along said chamber toward said passageway during the rotation of the structure, and means for progressively moving material delivered through said passageway to the inner chamber along said inner chamber away from said passageway and over said openings during said rotation.

2. A device for continuously forming and compacting powdered materials into shapes of predetermined size comprising, in combination, a structure defining outer and inner elongate chambers separated by a common wall and connected at one end with an opening which serves as an exit for materials from the outer chamber and an entry to the inner chamber, an entry for materials adjacent the other end of the outer chamber, an exit for finished shapes adjacent the other end of the inner chamber, means for feeding materials at a predetermined rate of flow into said outer chamber, means for imparting rotary movement to the materials fed to said outer chamber, means for progressively moving materials in the outer chamber from their point of entry to their

point of exit to the inner chamber, means for progressively moving materials delivered from the outer chamber to the inner chamber from the point of entry in the inner chamber to the exit therefrom, means disposed in the path of said latter movement for returning to the outer chamber shapes smaller than said predetermined size, said means comprising a series of openings disposed in said common wall and dimensioned to receive and pass therethrough said smaller shapes, and an imperforate shield disposed in the outer chamber and adjacent said openings and spaced from said openings to form a wall extending around the openings in said common wall to form an intermediate chamber in said outer chamber and thereby to prevent the entry through said openings of materials flowing through said outer chamber.

3. In a device for forming and compacting powdered materials into shapes of predetermined size, in combination, a rotatable structure containing outer and inner elongate concentric chambers separated by a common wall and connected at one end with a passage serving as an exit for materials from the outer chamber and an entry for materials into the inner chamber, an entry for materials disposed at the opposite end of the outer chamber, an exit for finished shapes disposed at the corresponding end of the inner chamber, means for rotating said structure, means for progressively moving materials in the outer chamber from the entry to the exit of said chamber, means for progressively moving materials delivered to the inner chamber from the point of entry thereinto to the point of exit, openings disposed in said common wall between the point of entry and point of exit in said inner chamber said openings being dimensioned to permit the passage therethrough of materials smaller than said shapes of predetermined size, and means disposed in said outer chamber and spaced around said openings to prevent the passage therethrough of materials moving from said outer chamber.

4. A device for agglomerating powdered materials to shapes of predetermined size and comprising a rotatable cylinder open at one end to receive materials and closed at the other end, means for rotating said cylinder, an inner chamber disposed in and peripherally surrounded by said cylinder and open at the same end as the cylinder, a passageway disposed between the cylinder and the inner chamber at a point toward the closed ends thereof and adapted to transfer material from the cylinder to the chamber, openings disposed in the wall of the chamber at points between said passageway and the open end of the chamber, said openings being dimensioned to permit passage therethrough to the cylinder of agglomerated shapes of less than said predetermined size, means for maintaining a positive flow of materials from their point of entry into the cylinder toward and through said passageway and thence from their point of entry into the chamber to the open end thereof and over said openings, and means disposed adjacent said openings and out of said chamber to prevent entry through said openings to said chamber of materials flowing through the cylinder said means being an imperforate wall spaced from the outer wall of said chamber.

FRANK DERFLER.
